(57) **CLAIM**

The ornamental design for a container for an electronic device, as shown and described.

DESCRIPTION

FIG. 1 is a front perspective view of a container for an electronic device;

FIG. 2 is a rear perspective view thereof;

FIG. 3 is a front elevation view thereof;

FIG. 4 is a rear elevation view thereof;

FIG. 5 is a side elevation view thereof;

FIG. 6 is another side elevation view thereof;

FIG. 7 is a top plan view thereof; and,

FIG. 8 is a bottom plan view thereof.

Broken lines illustrate stitching that is part of the claimed design.
